CAN CRUSHER

Harvey Jordon Smith, Greensboro, N.C., assignor to
Modern Metal Products Company, Greensboro, N.C.,
a corporation of North Carolina

Filed Nov. 12, 1959, Ser. No. 58,303

Term of patent 14 years

(Cl. D55—1)

Figure 1 is a perspective view of a can crusher showing the front and one side thereof, embodying my new design;

Figure 2 is a front perspective view of the can crusher illustrating another side thereof and a partial top perspective view thereof;

Figure 3 is a top plan view of the can crusher; and
Figure 4 is a rear elevational view of the can crusher.

What I claim is:

The ornamental design for a can crusher, as shown.
